UNITED STATES PATENT OFFICE.

HUGO CECIL GIBSON, OF PHILADELPHIA, PENNSYLVANIA.

HEATING APPARATUS.

Application filed December 16, 1926. Serial No. 155,142.

My invention relates to that class of portable heaters which consist of a heating element within a flue of which the heating element may be an electrical resistance, Bunsen flame, slow burning carbon compound or the like, while the flue may be a tube of any material preferably non-combustible and comparatively a non-conductor of heat, and its object is to provide a ready and effective adjustment of both the temperature and rate of flow of the current of heated air emerging from the flue.

To the above ends, my invention consists of a flue or tube pivotally supported and provided with means for locking it in any desired adjusted position, means for securing a heating element at one end thereof, and an adjustable heat distributer at the opposite end.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Fig. 1, represents a perspective view of a heating apparatus embodying my invention.

Fig. 2, represents a longitudinal, sectional view of the flue of my novel heater, shown in elevation.

Fig. 3, represents on an enlarged scale a section on line 3—3 of Fig. 1.

Similar numerals of reference indicate corresponding parts.

1 designates my novel portable, electric heater consisting of a heating element 2 adapted for connection to a source of electric power, supported within and attached to an open ended tube or flue 3 having a distributer 4 at the end opposite to the heating element and adapted to interfere with the normal flow of hot air emerging from the flue. 5 designates a stand or support having an upright 6, in which is mounted an adjustable screw 7 passing through the support 6 and threaded into the tube 3 for the purpose of clamping said tube to said support at any desired angle in relation to the horizon.

It will be understood that upon clamping the tube 3 with its essential parts consisting of the heating element 2 and the distributer 4 to the support 6 in a vertical position, the air within the tube on being heated by means of electric energy applied to the heating element will emerge from the tube at maximum velocity, whereas upon clamping the tube 3 to the support 6 at an angle of say 45 degrees in relation to the horizon, the rate of flow of hot air from the tube will be reduced, while the temperature of such air as emerges will be increased as compared to the rate of flow of air and the temperature thereof attained when the tube 3 is operated as a heating device in the vertical position.

Similarly the rate of flow of air through the tube will be decreased and its temperature increased as the angle of the tube in relation to the horizon is decreased and vice versa.

It may be desirable to distribute or spread the stream of hot air emerging from the tube 3 so as to produce a current of warm air of reduced temperature and reduced rate of flow and for this purpose I employ the distributer 4 consisting of a core or cone 8 formed of sheet material, having a hole or holes 9 therein to allow the passage of a small proportion of the hotter air therethrough, while the major portion of the hot air passes over and around the cone thus becoming spread and admixing with the cooler air of the surrounding atmosphere with the effect of producing a current of relatively warm air of larger cross-sectional area than would be obtained without the use of the distributer. The distributer 4 is slidably supported within the tube 3 by arms or strips 10, which may be formed integrally with the material of the distributer or attached thereto and are adapted frictionally to engage the tube 3 by their inherent spring action, thus permitting adjustability of position of the distributer 4 in regard to its distance from the end of the tube 3.

The heating element 2 can be secured in the flue 3 by a spider 10^x or any other means which does not obstruct the inlet end of said flue, and the plug 11 and cord 12 afford a convenient means for connecting the device to a suitable source of electrical energy as a conventional lamp socket.

The spider 10^x in practice may be provided with the resilient arms 13 which fric-

tionally engage the inner wall of the flue as will be understood from Figures 1 and 2 said arms 13 being in tight frictional engagement with the flue so that the heating unit, spider 5 and arms as a unit can be readily assembled. If desired resilient arms 13 can be fixedly secured to the flue as by riveting, spot welding or other means.

It will now be apparent that I have devised a novel and useful construction of improvements in heating apparatus which embodies the features of advantage enumerated as desirable in the statement of the invention and the above description and while I have in the present instance shown and described the preferred embodiment thereof which has been found in practice to give satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. In a portable heater of the flue type, a flue, a heating element therein and means for adjusting the position of said flue for varying the temperature and rate of flow of the heated air without varying the current flow in said heating element.

2. In a portable heater of the open ended flue type, a flue, a heating element at one end thereof, means for adjusting the position of said flue for varying the temperature and rate of flow of the heated air without varying the current flow in said heating element and means for deflecting and distributing

the current of hot air emerging from said flue.

3. In a device of the character stated, a support, an open ended flue pivotally mounted on said support, means for locking said flue in any desired position with respect to said support, a heating element in one end of said flue, and a distributor mounted in opposite end of said flue.

4. In a device of the character stated, an open ended flue, a heating element in one end thereof, a conical distributor slidably mounted in the other end thereof, the apex of the cone being adapted to be positioned within said flue, and resilient arms attached to the distributor and in frictional contact with the wall of said flue.

5. In a portable heater of the flue type, an adjustable flue, a heating element therein, and means for varying the angular relation of the flue to the horizon, thereby adjusting the temperature and rate of flow of the heated air.

6. In a portable heater of the flue type, an adjustable flue, a heating element therein, and means for varying the angular relation of the flue to the horizon, without varying the current flow in said heating element, thereby adjusting the temperature and rate of flow of the heated air.

7. In a portable heater of the flue type, a flue, a heating element therein, and means for varying the angular relation of the flue to the horizon, without varying the current flow in said heating element, and a distributor mounted in the end of said flue opposite to the heating element.

HUGO CECIL GIBSON.
